WATCH

Henry Federman, New York, N. Y.

Application May 14, 1954, Serial No. 30,504

Term of patent 14 years

(Cl. D42—8)

To all whom it may concern:

Be it known that I, Henry Federman, a citizen of the United States, residing at 345 East 57th Street, city of New York, State of New York, have invented a new, original, and ornamental Design for a Watch, as shown in the accompanying drawing, wherein:

Figure 1 is a side elevational view of a watch embodying my new design taken from the left of Figure 2.

Figure 2 is a top plan view of the watch, and

Figure 3 is a side elevation thereof, taken from the right of Figure 2.

The dominant features of the design reside in the portions shown in full lines.

I claim:

The ornamental design for a watch, as shown and described.
